UNITED STATES PATENT OFFICE.

NATHAN A. KURMAN, OF NEW YORK, N. Y.

SOUND-REPRODUCING DEVICE.

Application filed December 2, 1922. Serial No. 604,632.

To all whom it may concern:

Be it known that I, NATHAN A. KURMAN, a citizen of the United States, residing at the city of New York, borough of Manhattan, in the county and State of New York, have invented certain new and useful Improvements in Sound-Reproducing Devices, of which the following is a full, clear, and exact specification.

10 This invention relates to improvements in sound receiving and transmitting instruments, such as telephone receivers and transmitters, microphone repeaters, and more particularly to those instruments which are 15 adapted for use in loud-speaking systems or any loud transmission systems, and the same has for its object more particularly to provide an apparatus of the character specified which shall be comparatively simple in construction, efficient in operation, and easily 20 regulated or adjusted to meet the varying conditions of service.

Further, said invention has for its object to provide counterbalancing means effective 25 to counterbalance not only the tension due to the influence or attraction of the permanent magnet but also the tension due to the initially impressed voltages on the electromagnetic circuit, such as the voltage impressed upon the coil of the receiver which 30 is operatively associated with the plate circuit of an audion tube.

Further, said invention has for its object to provide an instrument in which the magnetic influence upon the armature and associated parts may be accurately counterbalanced 35 in order to render the diaphragm more sensitive so that sounds of greater volume and purer tone may be produced.

40 Further, said invention has for its object to provide an instrument in which the magnetic influence upon the armature and associated parts may be adjusted without placing 45 the diaphragm under tension or unduly affecting the resiliency thereof.

Further, said invention has for its object to provide an instrument embodying a leverage whereby the vibrations of the armature of the permanent magnet may be taken up 50 by a member heavy enough to convey all vibrations to a light member connected to the diaphragm, so that the latter may operate with greater efficiency.

Further, said invention has for its object 55 to provide an instrument embodying a lever-

age between the armature and the diaphragm wherein the tension of the armature of the permanent magnet thereon places no bending stress upon the leverage member connected to said diaphragm so as not to affect 60 the resiliency of said member. The full resiliency of said member is therefore available to transmit vibrations to the diaphragm.

Other objects and advantages will in part 65 be obvious and in part be specifically pointed out in the specification.

To the attainment of the aforesaid objects and ends my invention consists in the novel 70 details of construction, and in the combination, connection and arrangement of parts hereinafter more fully described and then pointed out in the claims.

In the accompanying drawings—

Figure 1 is a sectional view showing one 75 form of telephone receiver embodying my invention;

Fig. 2 is an enlarged detail sectional view on the line 2—2 of Fig. 1, showing the adjusting means;

Fig. 3 is a detail perspective view of the adjusting means and support;

Fig. 4 is a view similar to Fig. 1, showing a modified structure, and

Fig. 5 is an enlarged detail face view of 85 the adjusting means shown in Fig. 4.

Referring to Fig. 1, there is shown a permanent magnet 10 having one leg provided with an extension 11 and the other leg provided with a pole-piece 12 surrounded by a coil 13. The extension 11 has an armature 14 pivotally mounted thereon as by a notch and groove connection. Fixed to the magnet 10 is a frame 16 having at its upper end a plate 18 supporting a washer 19 and an apertured front plate 20. A diaphragm 22 is clamped between washers 19 by the plate 20. Within the aperture in plate 20 is secured a short tube 25 which is adapted for connection to some type of resonator.

Upon a knife-edge 30 formed on a member fixed to frame 16 is pivoted a lever 31 having a bifurcated arm to one side of the pivot, and a single arm 32 in the form of a spring to the other side of the pivot. The bifurcated arm consists of a light member 33 connected by an eye-bolt 35 to the diaphragm 22, and a heavy member 34 connected by a link 36 to a pin 37 on the end of armature 14 opposite the pole-piece 12. An 110

adjusting screw 40 passes through plate 18 and engages the outer end of the spring 32.

In operation, the adjusting screw is operated to raise the bifurcated arm until armature 14 is held a proper distance above the pole-piece 12, thus neutralizing the attraction of the magnet. During this operation the eye-bolt is disconnected from the diaphragm by loosening the nuts 41 which clamp said bolt to said diaphragm. When the armature has been counterbalanced by screw 40, the nuts may be tightened and the diaphragm is then free of all mechanical stress. It will be obvious that the resilient compensating adjustment will operate equally well to counterbalance the attraction of armature 14 (and hence, the tension on the diaphragm) due to some initially impressed voltage such as is sent through the coil 13 in radiotelephone systems. Since the link 36 is not connected to arm 33 there is at no time any bending stress in the arm connected to the diaphragm, so that the resiliency of said arm is not diminished. The arm 33 can therefore be made light and resilient and so add to the sensitivity and efficiency of the diaphragm, while the arm 34 can be constructed heavy enough to transmit the vibrations from the armature to the diaphragm.

A modified structure is illustrated in Figs. 4 and 5. All of the parts in these figures are the same as in Fig. 1 with the exception of the mounting for the lever and the spring adjustment. In this instance the lever comprises only the bifurcated arm consisting of the light upper member 33 connected to the diaphragm and the heavy member 34 connected to the armature. The bifurcated arm extends outside of frame 16 and is pivoted on knife edges 50 upon the outside of said frame forming a horizontal pivotal axis. To rock said lever about said axis to vary the pull upon the armature, for the purposes hereinbefore described, there are provided leaf springs 51 and 52 both fixed at one end to said lever. The spring 51 extends upwardly while the spring 52 extends downwardly. Cooperating with the free ends of said springs are adjusting screws 53, 54 extending into a bracket 55. The enclosing casing or base may be provided with apertures 56 for the introduction of a screwdriver or other instrument to actuate said screws 52, 53. It will be obvious that by varying the tension upon said springs any desired position of the lever may be obtained.

The above description illustrates the principles embodied in my invention but it will be understood that various changes and modifications may be made within the scope of the invention as defined in the annexed claims.

Having thus described my said invention

what I claim and desire to secure by Letters Patent is:

1. An apparatus of the character described, comprising a sound-responsive member, a diaphragm, and means acting on said member to counterbalance the magnetic forces acting thereon; said diaphragm when inactive being unstressed, substantially as specified. 70

2. An apparatus of the character described, comprising a sound-responsive member, a diaphragm, a connecting member between said sound-responsive member and said diaphragm, and means included in said connecting member to counterbalance the 80 magnetic forces acting on said sound-responsive member without placing said diaphragm, when inactive under appreciable stress, substantially as specified. 75

3. An apparatus of the character described, comprising a sound-responsive member, a diaphragm, means connecting said diaphragm and said sound-responsive member, means acting on said sound-responsive member to counterbalance the magnetic 90 forces acting thereon, and means for maintaining said diaphragm normally free of mechanical stresses, substantially as specified. 85

4. An apparatus of the character described, comprising a sound-responsive member, a diaphragm, means connecting said diaphragm and sound-responsive member, means for maintaining said diaphragm normally free of mechanical stresses, and means for adjusting said connecting means to counteract the magnetic forces acting on said sound-responsive member while maintaining the diaphragm in said normal condition, substantially as specified. 95 100 105

5. An apparatus of the character described, comprising a sound-responsive member, a diaphragm, means connecting said diaphragm and sound-responsive member, means for exerting a permanent magnetic 110 influence on said sound-responsive member, and means for balancing said member against said permanent magnetic influence without appreciably stressing said diaphragm substantially as specified. 115

6. An apparatus of the character described, comprising a sound-responsive member, a diaphragm, means connecting said diaphragm and said sound-responsive member, means for exerting a permanent 120 magnetic influence and means for impressing a constant electromagnetic influence on said sound-responsive member, and means for balancing said sound-responsive member against said magnetic and electromagnetic influence without materially stressing said diaphragm substantially as specified. 125

7. An apparatus of the character described, comprising a sound-responsive member, a diaphragm, a movable member, 130

- arms extending therefrom, a flexible connection between one of said arms and said sound-responsive member, and a flexible connection between the other of said arms and said diaphragm, substantially as specified. 40
8. An apparatus of the character described comprising a sound-responsive member, a diaphragm, a movable member, arms extending therefrom; one of said arms being lighter than the other and connected to said diaphragm, and means adapted to exert a stress transversely of the other of said arms connecting the same to said sound-responsive member, substantially as specified. 45
9. An apparatus of the character described comprising a sound-responsive member, a diaphragm, a movable member, arms extending therefrom, a connection between one of said arms and said diaphragm, and a connection between the other of said arms and said sound-responsive member, and means for adjusting said movable member to counterbalance said sound-responsive member, substantially as specified. 50
10. An apparatus of the character described, comprising an electromagnet, an armature therefor, a diaphragm, resilient means connecting said armature and diaphragm, and means for adjusting said connecting means to counterbalance the initial attraction of said electromagnet for said armature without affecting said diaphragm, substantially as specified. 55
11. An apparatus of the character described, comprising an electromagnet, an armature therefor, a diaphragm, a connecting member between said armature and said diaphragm comprising a lever having one of its arms bifurcated, one of said bifurcations being flexibly connected to said diaphragm and the other of said bifurcations being flexibly connected to said armature, substantially as specified. 60
12. An apparatus of the character described, comprising an electromagnet, an armature therefor, a diaphragm, a connecting member between said armature and said diaphragm comprising a lever having one of its arms bifurcated, one of said bifurcations being connected to said diaphragm and the other of said bifurcations being connected to said armature, and means for applying a tension to said last-named bifurcation without placing said first-named bifurcation under stress, substantially as specified. 65
13. An apparatus of the character described, comprising an electromagnet, an armature therefor, a diaphragm, a connecting member between said armature and said diaphragm comprising a lever having one of its arms bifurcated, one of said bifurcations being connected to said diaphragm, the other of said bifurcations being connected to said armature, resilient means for applying a tension to said last-named bifurcation to counterbalance said armature, means to permit of the disconnection of said diaphragm from said first-named bifurcation, and means for varying said tension at will, substantially as specified. 70

Signed at the city of New York, in the county and State of New York, this sixth day of October, one thousand nine hundred and twenty-two. 75

NATHAN A. KURMAN.
